UNITED STATES PATENT OFFICE.

GEORGE A. RICKER, OF BUFFALO, NEW YORK.

DESIGN FOR A BRACKET FOR ELECTRIC WIRES AND CABLES.

SPECIFICATION forming part of Design No. 35,028, dated September 3, 1901.

Application filed May 10, 1901. Serial No. 59,710. Term of patent 3½ years.

To all whom it may concern:

Be it known that I, GEORGE A. RICKER, a citizen of the United States, residing in the city of Buffalo, in the county of Erie and State 5 of New York, have invented and produced a new and original Design for a Bracket for Electric Wires and Cables, of which the following is a full, clear, and exact description.

My invention relates to a design for brackets for electric wires and cables; and it consists, essentially, of the construction shown in the drawings herewith, in which like characters of reference indicate like parts.

Figure 1 is a perspective view. Fig. 2 is 15 an elevation with the bracket in the position for holding a cable in a horizontal position. Fig. 3 is a plan view of Fig. 2.

The design consists of a hollow cylindrical body A and a hollow cylindrical body B, which 20 have their axes at right angles to each other. They are joined by a neck C. Each of the cylindrical castings is split longitudinally, as shown at a and b, and is provided with ears c and d.

D is an insulating-spool having flanged 25 ends and split longitudinally to correspond to the split b of the body B. The spool D is inserted and firmly held in the body B.

Having thus described my invention, what I claim is—30 The design for a bracket for electric wires and cables, substantially as shown and described.

In witness whereof I have hereunto set my hand, in the presence of two witnesses, this 35 25th day of April, 1901, at the city of Buffalo, in the county of Erie and State of New York.

GEORGE A. RICKER.
